ABSTRACT OF THE DISCLOSURE

Higher molecular weight hydrocarbonaceous materials containing polynuclear substances, such as heavy petroleum crudes and higher boiling petroleum fractions, including residual fractions, shale oil, tar sand oil, oil and tar from coal and coal itself are hydrocracked at an elevated temperature ranging from 250° C. to 500° C. and in the presence of hydrogen at a pressure of 200 to 3000 p.s.i.g., while intimately mixed with a homogeneous continuous liquid phase catalyst system comprising predominately one or more phosphoric acids thermally stable under the hydrocracking conditions, such as, pyrophosphoric acid and polyphosphoric acids having an empirical ratio of $H_2O:P_2O_5$ of 3 or less, and a minor proportion, e.g., 10% by weight of certain metal polyhalides which are active hydrocracking catalysts, e.g., especially zinc, gallium and antimony halides.

BACKGROUND OF THE INVENTION**Field of the Invention**

This invention relates to the catalytic hydrocracking of higher boiling petroleum oils, shale oil, tar sand oil, coal and oil from coal in the presence of certain metal halide catalysts.

Description of Prior Art

Heavy petroleum oils, tar sand oils, shale oil, coal, and coal extracts can be hydrocracked in the presence of various polyvalent metal halides. For example, U.S. Pats. 3,355,376; 3,371,049; 3,594,329 and 3,625,861 and British Pat. 1,095,851 disclose the use of molten zinc chloride or zinc bromide in hydrocracking coal extracts. U.S. 3,619,411 and 3,542,665 disclose the use of antimony trichloride, tribromide or triiodide, bismuth trichloride or tribromide, or arsenic triiodide, in a continuous liquid phase as catalyst in the hydrocracking of high-boiling hydrocarbons and of coal. U.S. 3,657,108 and 3,685,962, which are directed to certain methods of regenerating certain spent metal halide catalysts used in hydrocracking, disclose *inter alia*, the use of zinc chloride, bromide or iodide as liquid phase catalyst for hydrocracking coal. Still further, the addition of certain melting point depressants to molten zinc halide hydrocracking catalysts in hydrocracking heavy oils is disclosed in U.S. 3,677,932 and also in Netherlands Application 70/10318, published Jan. 19, 1971. This latter patent application also discloses promoting, the hydrocracking activity of zinc chloride, zinc bromide, zinc iodide, antimony chloride, antimony bromide, antimony iodide, bismuth chloride, bismuth bromide, tin bromide, titanium iodide, arsenic bromide, arsenic iodide, mercuric bromide, mercuric iodide, and gallium bromide with small amounts of a mineral acid, preferably corresponding hydrogen halides and pyrophosphoric acid.

There are various advantages obtainable by the use of a large body of a molten metal halide as catalysts and reaction medium for hydrocracking heavy natural oil-containing or oil-precursor material, particularly high polynuclear substances, such as heavy petroleum oil, including crude oils and fractions thereof, shale oils, tar sand oils, coal extracts and coal. On the other hand, there are still many obstacles to commercialization, as will be apparent

2

from the many publications in this field, including the aforementioned patents.

SUMMARY OF THE INVENTION

It has now been found that there are still further advantages obtainable in the use of metal halides as hydrocracking catalysts, by the use of the metal halide catalyst dissolved in a relatively large proportion of molten pyrophosphoric acid as a medium for carrying out the hydrocracking. By "pyrophosphoric acid" as employed in the specification and claims is meant $H_4P_2O_7$, or the equilibrium mixtures of ortho-, pyro- and polyphosphoric acids corresponding empirically thereto, or other mixtures of the various phosphoric acids in which the substance is represented by the average formula nH_2O/P_2O_5 wherein n has a positive value 3 or less and the mixture contains a substantial amount of molecular species wherein n is from 1 to 2, inclusive. The compositions and physical properties of such phosphoric acid mixtures are described in "Encyclopedia of Chemical Technology," by Kirk and Othmer, 2nd Edition, 1968, vol. 15, pages 241 and 242.

This invention is based on the discovery that molten pyrophosphoric acid at 250° to 500° C. is uniquely useful as a medium for hydrocracking petroleum oils, shale oils, tar sand oils, coal oils and coal in the presence of an effective, relatively small, amount of the metal halides which are known to be useful hydrocracking catalysts for such materials. It makes it feasible to use a significantly smaller amount of the metal halide than when using the metal halide also as the reaction medium. Pyrophosphoric acid, as distinguished from sulfuric acid, is not reduced by the hydrogen or hydrocarbonaceous feed or products, nor is it adversely affected by nitrogen, sulfur or oxygen products of the conversion. Thus, if desired, carbonaceous residues can be oxidized (burned) from it without adversely affecting the acid. In addition, pyrophosphoric acid minimizes the reaction of formed ammonia with the metal halide which tends to reduce the activity of the metal halide. Any ammonium phosphates which are formed can be decomposed by heating to liberate ammonia and form phosphoric acid. The present pyrophosphoric acid based system is also advantageous in that any water formed (by hydrogenation of bound oxygen in the feed) will be chemically bound by the pyrophosphoric acid thus minimizing any adverse effect it may have on the metal halide catalyst, such as from hydrolysis. As an essentially non-oxidizing substance, pyrophosphoric acid (as distinguished from sulfuric acid) is compatible with the metal halides, even with metal iodides, without oxidation of the halide to free halogen. It also provides an acidic medium which allows mild cracking while obtaining efficient catalytic hydrogenation of the cracked fragments and other hydrogenable uncracked substances which makes it feasible to use a smaller proportion of a given catalytic metal halide. It also provides a system in which the acid function-catalyzed reactions and the catalyzed hydrogenation can be controlled or regulated with a greater degree of independence from one another. The use of pyrophosphoric acid also provides a system where metal halides which are high-melting or otherwise unsuitable for bulk use, can be utilized as catalysts.

DESCRIPTION OF PREFERRED EMBODIMENTS

The invention is practiced by intimately contacting a hydrocarbonaceous feed with hydrogen in a continuous-phase molten mixture predominating in pyrophosphoric acid containing a minor proportion of a polyvalent metal halide hydrocracking catalyst under hydrocracking conditions including a temperature in the range from 250° to 500° C. and a pressure of at least 200 p.s.i.g., e.g., from 200 to 3000 p.s.i.g. Hydrocarbonaceous feeds which can

be suitably processed include, for example, heavy oils and residues, coal, coal extracts, shale oil and the like.

The process can be carried out batchwise or continuously. Contacting of the charge material, catalyst and pyrophosphoric acid medium can be effected by various methods and means, including cocurrent and counter-current contacting. The reaction components can be introduced into the hydrocracking zone separately, or two or more of the reaction components can be pre-mixed before subjecting them to hydrocracking.

In one embodiment of the invention the charge material and hydrogen are continuously delivered to a body of the liquid pyrophosphoric acid and metal halide catalyst and the reaction products are continuously withdrawn in gaseous form and separated from the unconverted hydrogen which is recycled to the reaction zone. A portion of the organic material can also be recycled for further conversions if desired.

Exothermic heat of reaction can be removed as heat of vaporization or sensible heat of the gaseous and vaporous stream, and/or by providing suitable internal or external heat exchange between the hot liquid reaction medium and a suitable coolant to maintain the desired temperature in the reaction zone.

A slip-stream can be continuously withdrawn from the reaction zone and filtered or centrifuged to remove solid contaminants, such as carbon, ash and metal phosphates, and the separated liquid phase returned to the reaction zone. Accumulated tarry material in the reaction mixture may be removed by taking a slip-stream of the reactant mixture and extracting it with a suitable solvent such as a C₆ to C₈ aromatic hydrocarbon. Alternatively, carbonaceous residue can be burned from solids, which can be separated by filtration or centrifugation.

Make-up pyrophosphoric acid and metal halide catalyst can be added as required. The make-up acid can be provided by adding orthophosphoric acid to the reaction zone wherein it loses water at the elevated temperature to form pyrophosphoric acid, the excess water (regardless of source) being evolved with the volatile reaction products. Alternatively, or simultaneously, phosphorus pentoxide can be added which reacts with water derived from orthophosphoric acid, or uncombined water in the charge, or water resulting from conversion of bound oxygen with hydrogen. Make-up metal halide can be supplied directly to the reaction zone as such, either as solid or molten material, or it can be pre-mixed with make-up pyrophosphoric acid or carbonaceous feed.

If desired, hydrogen halide may be added to the system to minimize any reaction of the metal halide with pyrophosphoric acid. Some of the metal halides are more reactive than others with pyrophosphoric acid and also with other components of the reaction mixture, especially when water, ammonia or hydrogen sulfide are produced from oxygen, nitrogen or sulfur in the hydrocracking charge.

An important advantage of the present invention is that the pyrophosphoric acid reacts with and binds the formed water and ammonia thereby minimizing their deactivating

action on the metal halide and making it possible to utilize a smaller amount of metal halide than would be the case if the metal halide were employed alone.

The catalytic system in accordance with the invention is a continuous phase liquid composed predominantly of pyrophosphoric acid and a minor proportion, generally from about 1% by weight to about 30% by weight, preferably from 5% to 20% by weight, of a polyvalent metal halide hydrocracking catalyst which is compatible with the pyrophosphoric acid under hydrocracking conditions. It is known that the various metal halides already disclosed to be hydrocracking catalysts differ considerably in catalytic activity and hydrocracking selectivity, in melting point, in viscosity in the molten state at different temperatures and in chemical stability or reactivity in the presence of various substances which are encountered in hydrocracking various stocks. These factors require consideration in the selection of the metal halide and its concentration and conditions of use. Thus, antimony trichloride is a relatively active cracking catalyst but is rather susceptible to deactivation by water due to hydrolysis. Antimony tribromide is more resistant to deactivation by hydrolysis and more active as a hydrogenation catalyst. Zinc iodide, for instance, is fairly resistant to deactivation by water, ammonia and hydrogen sulfide and is highly active as a hydrogenation catalyst, but is relatively less active as a cracking catalyst. Such differences influence the selection of metal halide proportions and conversion conditions. For example, antimony chloride is active even at temperatures as low as 250° C., while antimony tribromide is preferably used at 275° to 400° C., especially about 325° to 375° C. Zinc iodide, on the other hand, can be employed at about 350° to 500° C., preferably at about 400° to 450° C.

The extent to which the hydrocracking charge dissolves in or reacts with the catalyst system depends in part on the oxygen, nitrogen and sulfur contents of the charge. Petroleum oils low in these elements are relatively insoluble resulting in a heterogeneous reaction mixture. On the other hand, coal, coal extracts and shale oil which contain large proportions of such polar atoms are more soluble in the highly polar pyrophosphoric acid.

The method of practicing the invention and the results obtained thereby are illustrated by the following examples.

A series of experiments were conducted in which 20 grams of coal (Illinois No. 6, moisture free, 100-200 mesh, 15% ash) was hydrocracked in pyrophosphoric acid alone (Experiment 1), in molten SbBr₃ alone (Experiment 2) and in pyrophosphoric acid containing various metal halides in accordance with the invention (Experiments 3-7). Hydrocracking was effected in each of the experiments at a temperature of 350° C., a pressure of 1800-2000 p.s.i.g. for a period of one hour, except for Experiment 1 in which the time was 30 minutes. The composition of the respective catalyst systems and the products obtained from hydrocracking are shown in the following table. The hydrocracked products are reported in units of grams per 100 g. of moisture and ash-free (MAF) coal.

TABLE A

Experiment	1	2	3	4	5	6	7
Catalyst type		SbBr ₃	SbBr ₃	SbBr ₃	GaBr ₃	GaI ₃	TlF ₄
Amount, g.	0	150	10	40	5	8	31
H ₄ P ₂ O ₇ , g.	107	0	150	150	150	150	150
Products, g./100 g. MAF coal:							
CH ₄ +C ₂ H ₆	Tr. ^a	1.2	0.8	1.4	0.5	1.8	0.5
C ₃ H ₈	0.1	1.7	1.9	2.1	1.5	3.1	1.7
i-C ₄ H ₁₀	0.05	4.0	2.5	2.7	2.1	3.6	2.8
n-C ₄ H ₁₀		1.4	0.3	0.9	0.2	0.5	0.2
i-C ₅ H ₁₂	0.04	3.7	1.2	1.8	1.3	1.6	1.2
n-C ₅ H ₁₂		0.6	0.1	0.4	0.1	0.1	0.1
C ₆ H ₁₄	0.01	3.3	0.9	1.6	1.0	0.8	0.5
MCP (methyl cyclopentane)	0.01	6.2	1.2	2.1	1.2	0.8	0.3
C ₇ H ₁₆ +C ₈ H ₁₈	Tr.	15.8	3.9	7.5	6.3	1.9	0.9
C ₉ H ₂₀ to 250° C. boiling range hydrocarbons		17.0	7.6	8.0	10.0	3.3	1.1
Total C ₄ H ₁₀ to 250° C. boiling range hydrocarbons	0.1	52.0	17.7	24.9	22.2	12.7	7.0
H ₂ consumed, g./100 g. MAF coal	1.5	9.3	8.5	10.4	8.3	7.7	7.8
Maximum rate of H ₂ uptake, p.s.i.g./min.	4	109	78	96	17	27	20

^a Tr=trace.

The results in Experiments 3 and 4 indicate that neither the hydrogenation rate nor the amount of hydrogen uptake decreased greatly for the $H_4P_2O_7$ - $SbBr_3$ system as compared to the undiluted $SbBr_3$ system of Experiment 2. While the amount of cracking decreased by two-thirds in Experiment 3, this is considerably less than the decrease in $SbBr_3$ concentration (a factor of about 15). Moreover, the iso/normal ratios in the C_4 and C_5 products were extremely high, indicating that the cracking which occurred was acid-promoted.

The results of Experiment 5 show that a relatively expensive catalyst such as $GaBr_3$ can be used in the form of a dilute solution of pyrophosphoric acid and still maintain reasonably good activity. This illustrates the advantage of the present invention in using an active but expensive catalyst under conditions such that overall catalyst costs will be low.

A further advantage of the use of pyrophosphoric acid as the reaction medium is demonstrated in Experiment 7. The TiF_4 catalyst employed in this experiment is very difficult to use in bulk in that it sublimes at $284^\circ C$. without melting. However, this catalyst can be efficaciously employed when dissolved in pyrophosphoric acid as shown in Experiment 7, although the hydrogenation and cracking rates are lower than obtained with the other metal catalysts.

What is claimed is:

1. In a process for hydrocracking higher molecular weight hydrocarbonaceous materials containing polynuclear substances by contacting said materials in the presence of hydrogen with a continuous liquid phase catalyst system containing a polyvalent metal halide as the essential hydrocracking catalyst under hydrocracking conditions including a temperature in the range of $250^\circ C$. to $500^\circ C$. and a pressure of from 200 to 3000 p.s.i.g., the improvement which comprises providing the metal halide

catalyst in homogeneous liquid phase mixture with a major proportion of at least 70% by weight of pyrophosphoric acid.

5 2. The process of claim 1 wherein the catalyst system is essentially 5-30% antimony trihalide in homogeneous liquid phase mixture with at least 70% by weight of pyrophosphoric acid.

3. The process of claim 2 wherein the antimony trihalide is antimony tribromide.

10 4. The process of claim 1 wherein the catalyst system is essentially 5-30% by weight zinc halide in homogeneous liquid phase mixture with at least 70% by weight pyrophosphoric acid.

15 5. The process of claim 4 wherein the zinc halide is zinc iodide.
